DUST GUARD FOR JOURNAL BOXES

Cleon M. Hannaford, Toledo, Ohio; Marie L. Hannaford, executrix of said Cleon M. Hannaford, deceased

Application October 21, 1941, Serial No. 415,951

5 Claims. (Cl. 286—6)

This invention relates to journal boxes and more particularly to a means for excluding dust and foreign matter from a journal box.

The invention comprehends the provision of means surrounding the car axle at its entrance into the journal box for the purpose of excluding foreign matter from the journal box and as an aid in preventing loss of lubricant therefrom.

The invention has for an object the provision of means formed of sheet metal providing a support for fibrous material which is arranged to contact the exterior periphery of a car axle forming a dust excluding means for a journal box.

A further object of the invention is the provision of a dust guard of fibrous material supported by sheet metal means which may be used in conjunction with a conventional wood dust guard or which may be used without such wood dust guard.

Another object of the invention is the provision of dust guard means for railway car axle journal boxes embodying sheet metal supporting means for a fibrous guard structure wherein the sheet metal means may be easily and quickly assembled or removed for purposes of repair or replacement and yet is of a construction which is securely held in operative position in the journal box.

Still another object is the provision of a dust guard embodying flexible fibrous material in normal contact with the car axle which is adapted to be readily flexed to accommodate relative movements of the axle.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

Figure 1 is an elevational sectional view of a journal box incorporating the dust guard construction of my invention;

Figure 2 is an enlarged fragmentary vertical sectional view illustrating the details of the dust guard construction;

Figure 3 is a front elevational view of the dust guard construction of my invention;

Figure 4 is a fragmentary sectional view illustrating a means of securing flexible fibrous material to the sheet metal dust guard frame, the

section being taken substantially on line 4—4 of Figure 3;

Figure 5 is a view similar to Figure 3 showing a modified form of fibrous material forming an element of the dust guard structure.

Figure 6 is an enlarged fragmentary view showing a portion of the structure illustrated in Figure 4.

Referring to the drawing in detail, 10 designates a journal box for a railway car, the box having an opening in its front wall which is adapted to be closed by a door 11 hingedly connected to the upper portion of the journal box by means of a pin 12, the journal box being adapted to be attached to or form a part of a truck side frame of the car. The car axle 14 has a journal portion 15 extending into the box through an opening in the rear thereof, and above the journal portion 15 is positioned a bearing brass 16 which abuts a backing plate 17 positioned adjacent the upper wall of the journal box. The end of the journal portion of the axle is provided with a shoulder or flange 18 for properly positioning the bearing brass 16 with respect to the journal portion 15.

The journal box is provided with a pair of parallel inwardly extending flanges or abutment walls 19 and 20 providing a vertically arranged space or channel 21 therebetween for receiving 30 dust guard means utilized for the purpose of excluding dust and foreign matter from the journal box. The present invention is directed to novel dust guard means which may be utilized in journal boxes of present conventional construction with slight modification as well as new journal boxes. In the form of the invention as shown in Figures 1 to 4, inclusive, I have provided a dust guard frame structure 22 preferably fabricated of sheet metal of U-shaped configuration having 35 side wall portions 23 and 24 connected by an integral bight portion 25 as is especially shown in Figures 2 and 4. The walls 23 and 24 are provided with centrally arranged circular openings defined by edge portions 26 and 27. The side wall portions 23 and 24 are formed with raised or offset annular boss portions 28 and 29 bounding the circular openings and which are adapted to engage in circular recesses 30 and 31 formed in the opposing inner walls of the abutments or vertical wall portions 19 and 20 formed on the journal box. These annular recesses 30 and 31 are arranged to snugly receive the annular raised or boss portions 28 and 29 of the sheet metal dust guard frame. As the dust guard frame is formed of sheet metal, the resilience or "spring" of the

frame serves to hold the latter securely in position in the space or channel 22. The upper extremities of the frame terminate in laterally extending ears or projections 33 which facilitate the assembly or removal of the dust guard construction.

The edges of the annular bosses 28 are integrally formed with offset portions or ears 34 and positioned between these ear portions and the body portions of the bosses and securely held therebetween is an element 35 formed of flexible fibrous material as, for example, felt, cotton, wicking or the like. The element is preferably supported or provided with a backing member 36 formed of relatively thin sheet metal or the like which is bent or crimped over the periphery of the element 35 to reinforce the same. The element 35 may be of annular configuration or may be a single strip of material with the ends in abutting relation. The element 35 is configurated to surround the axle and of a dimension to fit or contact the exterior cylindrical surface of the car axle 14 as shown in Figure 2. Through this arrangement the circular interior edges of the wicking 35 form a close contact with the axle to prevent the ingress of dust or other foreign matter into the journal box as well as to minimize the loss of lubricant through the wiping action of the wicking on the car axle.

As particularly shown in Figure 2, the arrangement of my invention permits, if desired, the use of the conventional dust guard 40 indicated in broken lines and is formed of wood or the like. It is to be noted however that in the use of the conventional dust guard made of wood, a suitable annular space 41 is provided for accommodating the car axle which space is larger than the car axle to permit relative movements of the car axle without engagement of the axle with the guard. Thus the conventional wood dust guard does not seal the journal as does the dust guard of my invention wherein the wicking or fibrous material is fabricated in a manner which in normal position engages the car axle throughout its circumference. In the operation of a railway car, the car axle is capable of movement relative to the journal box and with the use of the dust guard of my invention, the wicking is only temporarily distorted to permit such relative movements of the axle with respect to the journal box. Through the use of my invention, the dust guard element 35 contacts the exterior periphery of the axle in normal position, such contact being interrupted only when the axle moves out of normal position as when the car is on a curve, and the contact is then only momentarily disrupted, and is re-established with the axle in normal position.

In the form of the invention shown in Figure 5, the sealing element 35' is formed of material having a large number of strands 48 preferably radially arranged with respect to the rotating axis of the car axle, the inner ends of the strands 48 being arranged to have a wiping contact or engagement with the car axle periphery to establish a guard or seal to prevent the entrance of dust and foreign matter into the journal box. The radially arranged strands 48 of the element 35' are preferably of sufficient length to engage the periphery of the car axle and be slightly distorted thereby to provide an effective contact between the strands and the axle. In the event of relative movement of the car axle with respect to the journal box the radially arranged strands will merely be flexed or caused to move temporarily out of their normal position in engagement with

the car axle. When the axle has moved to its normal central position in the journal box the strand material will again contact the axle throughout its periphery.

5 While the arrangement of my invention is intended to be used independently of other dust guard means, the same may be used with the conventional wood dust guard 41 as shown in Figure 2. The dust guard arrangement of my invention may be quickly and easily assembled in place by gripping the ear portions 33 and flexing or springing portions 23 and 24 together as shown in broken lines in Figure 2, which flexing of portions 23 and 24 moves the annular boss portions 28 and 10 29 inwardly toward each other and permits the guard to be slid into place in the channel 21, in the specific embodiment here illustrated, and when the ear portions are released the bosses 28 and 29 spring outwardly into the recesses 30 and 31 in the walls 19 and 20, thus permitting the dust guard construction to be slidably assembled in the channel or space 22. The dust guard may likewise be easily removed by gripping the ear portions 33, springing the sides of the guard together thereby releasing the latch portions 28 and 25 29 out of the recesses 30 and 31 so that the guard may be slidably removed.

20 It is apparent that, within the scope of the invention, modifications and different arrangements may be made other than is herein disclosed, and the present disclosure is illustrative merely, the invention comprehending all variations thereof.

What I claim is:

35 1. In combination; a car axle journal box formed with a pair of substantially parallel abutment walls, said walls being spaced to form a channel therebetween and having an opening for the car journal; a frame structure formed of

40 sheet metal of U-shaped configuration arranged to be slidably received in the channel in said journal box, said abutment walls having frame retaining recessed means located about said opening; the side walls of said frame structure having outwardly extending annular portions adapted to extend into said recesses in the journal box walls; and means formed of fibrous material supported upon said U-shaped frame arranged for engagement with a car axle.

45 2. In combination with a car axle journal box said journal box being integrally formed with a vertically arranged channel and having a car axle opening therein; a frame structure formed of sheet metal arranged to be slidably received in the channel in said journal box; the walls defining said channel having frame retaining recessed means located about said opening formed therein; the side walls of said frame structure having raised portions adapted to extend into said recesses; and means formed of fibrous material supported upon said frame structure arranged for engagement with a car axle.

50 3. In combination, a railway car axle journal box having a pair of vertical substantially parallel walls spaced to provide a channel therebetween and having an opening for the car journal; a one-piece U-shaped frame formed of sheet metal arranged to be slidably received in said channel; the interior opposed surfaces of said channel walls having frame retaining recessed means located about said opening, the side walls of said frame structure having outwardly extending raised portions adapted to extend into said recesses, and 55 70 75 an annularly shaped element of fibrous material

carried by each of the side walls of said frame structure and arranged for engagement with the periphery of a car axle.

4. In combination, a railway car axle journal box having a pair of vertical substantially parallel walls spaced to provide a channel therebetween and having an opening for the car journal; a U-shaped frame formed of flexible sheet metal arranged to be slidably received in said channel; the interior opposed surfaces of said channel walls having frame retaining recessed means located about said opening, the side walls of said frame structure having outwardly extending raised portions adapted to extend into said recesses, the flexure of the U-shaped sheet metal frame resiliently retaining the annular raised portions in the recesses in the walls of said channel, an annularly shaped element of fibrous material carried by each of the side walls of said frame structure and arranged for engagement with the periphery of a 20 car axle.

5. In combination, a railway car axle journal box having a pair of vertical substantially parallel walls spaced to provide a channel therebetween; a one-piece U-shaped frame formed of flexible sheet metal arranged to be slidably received in said channel; laterally projecting ear portions formed on said frame; the interior opposed surfaces of said channel walls having circular recesses, the side walls of said frame structure having outwardly extending raised portions adapted to extend into said recesses, the flexure of the U-shaped sheet metal frame resiliently retaining the annular raised portions in the recesses in the walls of said channel, said ear portions providing a gripping means to manually flex said side walls inwardly, and an annularly shaped element of fibrous material carried by each of the side walls of said frame structure and arranged for engagement with the periphery of a car axle.

CLEON M. HANNAFORD.
